(57) **CLAIM**

The ornamental design for a bottle portion, as shown and described.

DESCRIPTION

FIG. 1 is a top, front, right side perspective view of our bottle portion;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dash-dash-dash broken lines shown in the drawings are included for the purpose of illustrating environmental structure and form no part of the claimed design.

The dot-dash-dot-dash broken lines shown in the drawings represent the unclaimed boundaries of the claimed design.

1 Claim, 3 Drawing Sheets
